UNITED STATES PATENT OFFICE.

ROBERT C. MATHEWS, OF NEW YORK, N. Y., ASSIGNOR TO WESTERN ELECTRIC COMPANY, INCORPORATED, OF NEW YORK, N. Y., A CORPORATION OF NEW YORK.

SIGNALING SYSTEM.

Application filed March 24, 1921. Serial No. 455,136.

To all whom it may concern:

Be it known that I, ROBERT C. MATHEWS, a citizen of United States, residing at New York city, in the county of Bronx, 5 State of New York, have invented certain new and useful Improvements in Signaling Systems, of which the following is a full, clear, concise, and exact description.

This invention relates to signaling systems and more particularly to systems employed in connection with long distance telephone lines.

With long distance telephone lines, where it is the practice to use conductors composed for both telephone and telegraph operation, it has been found necessary, to avoid disturbing the telegraph instruments, to use signaling current of a frequency considerably higher than 16 cycles per second, 20 which is the approximate frequency of the current generally used to operate the ordinary type of low frequency telephone ringer. To signal over composited lines with the higher frequency current, it has 25 been the practice to use a receiving circuit in which is connected a relay having an armature tuned to respond to current of approximately 135 cycles per second.

To maintain satisfactorily this system, it 30 is necessary that the tuned relay and its associated relays be maintained in careful adjustment to prevent interference from low frequency current or stray line currents due to the telegraph operation or some external source. With the advent of telephone lines upon which repeaters are installed, and which are designed for most effective operation on currents of voice frequency range, it is found necessary to 35 provide a special circuit at repeater stations to have efficient means for ringing through the repeater station with the current of 135 cycles.

It is the object of this invention to provide 40 an improved signaling system similar to but more easily maintained, than the system described above, and which is more free from interference, and is better adapted for operation on lines to which repeaters or other apparatus designed for voice frequency currents are connected.

Broadly, it is the object of this invention to provide a signaling system in which a receiving device responds to a predetermined, selected and combined effect of sev-

eral electrical impulses applied to the transmission medium simultaneously, with means for preventing the response of the receiving device to impulses having frequency components differing from those on which the receiving device is designed to respond.

To attain this object, current impulses of various selected frequencies are applied to the transmission medium simultaneously, and the receiving apparatus is designed to respond to some predetermined joint effect resulting from the combination of the various component impulses. For example, in the case of two currents of different frequency, the receiving circuit may be designed to respond to the difference frequency. Similarly, other resultant effects of the combining of the several components may be selected and used to operate the receiving apparatus. To avoid false signaling, the receiving circuit is designed so that it responds to the impulse of predetermined frequency only when that is obtained as a result of the combining of the particular component frequencies of the same value as those selected for operation. In view of the fact that it is unlikely that the several components of the interfering impulses are identical with the several components of the operating impulses, the possibility of false operation is remote.

The nature of the invention will clearly appear from the following specification and the accompanying drawing, Figure 1 of which shows diagrammatically one embodiment thereof as applied to a telephone transmission line where in two speech frequency currents are simultaneously applied to the line. Fig. 2 shows a receiving circuit adapted to be employed in connection with the transmission line L when three speech frequency currents are substituted for the two current sources shown at 18, Fig. 1.

Figure 1 of the drawing shows how this 100 signaling system may be applied to a telephone transmission line L connecting two stations A and B. To signal the station B, the plug 34 of a cord circuit C, located at both stations A and B, but shown only at 105 station A, is inserted into a jack 1 and a ringing key 2 is actuated causing the operation of a relay 3 which applies from a source 18 two frequency current to the line L. This current passes by induction 110

through the windings of repeating coils 40 and 41 and over the line, to a receiving circuit X (which is shown within the dotted lines of the rectangle), through a selective circuit to a coil 10 and then through the circuits of thermionic tubes 11 and 12. The output side of tube 12 supplies unidirectional current to a relay 13 which operates and causes the release of a normally 10 operated relay 14, the operation of relay 35 and the lighting of the lamp 47, indicating that station A is calling. By selecting the two frequency components so that their difference frequency is below that of 15 the voice range, the selective circuit is, in general, not required since the input circuit of tube 12 then has low transmission efficiency for currents of voice range frequency.

20 The repeating coils 40 and 41 are shown connected in the line circuit to form with relays 42 and 43, and keys 44 and 45, one leg of a composite telegraph circuit. This circuit is shown merely to illustrate a source of 25 interfering currents, which the circuits of this invention prevent from causing a false operation of the line signals at stations A and B. It is thought that the invention may be more fully comprehended from the 30 following detailed description of the operation of the system.

Assuming that it is desired to signal the station B from the station A, plug 34 of cord circuit C is inserted into jack 1. Relay 15 35 then operates through the following circuit: from grounded battery, through the winding of relay 16, sleeve contacts of plug 34 and jack 1, and windings of relays 15 and 17 to ground. Relay 15 by its operation 40 connects, through its alternate contact, conductor 31, from the receiving circuit Y, to its lower winding terminal, the reasons for which will hereinafter appear. The marginal relays 16 and 17 do not operate at this 45 time. However, on the actuation of ringing key 2, the winding of relay 16 is short-circuited, by the connection of battery to the lower right-hand contact of the key 2, and relay 17 operates. Relay 3 operates through 50 an obvious circuit and applies to the conductors of transmission line L double frequency ringing current from the source 18. For purposes of description, it may be assumed that the component currents are of 55 700 and 1100 cycles per second frequency. These two components pass through the windings of repeating coils 40 and 41 and enter the receiving circuit X, shown within the dotted lines of the rectangle, through the 60 coil 8 of transformer 9. The 700 cycle current may be assumed to pass through a circuit composed of the coil 4 and condenser 5. The 1100 cycle component may be assumed to pass through the coil 6 in series with condenser 7. These circuits are resonant to

their respective frequencies and offer high impedance to other frequencies. A resultant current, due to the joint effect of the two components passing through coil 8, is induced in the secondary coil 10 of transformer 9. This induced current passes through the condenser 19 and shunting resistance 20 into the grid circuit of the tube 11. The effect of the condenser and resistance is to assist rectification in the grid circuit and to produce the current component of beat or difference frequency. In the plate circuit of the tube 11 is battery 21 in series with a condenser 22 shunted by an inductance 23. This plate circuit is designed to offer high impedance to the difference frequency and offer low impedance to other frequencies. Consequently, current of the beat or difference frequency is induced in the secondary coil 24 of the transformer 25. This induced current passes through the grid circuit of the tube 12 which includes a condenser 46 shunted by a resistance 26. This condenser and resistance in the grid circuit have the same rectifying effect as did condenser 19 and resistance 26 of the grid circuit of tube 11. The effect of this is to produce a direct current potential in the grid of this tube. In the plate circuit of tube 12 is connected the winding of the 95 relay 13 which is energized by the corresponding amplified unidirectional current. Although thermionic rectifying tubes are shown, it is to be understood that any other suitable rectifying device may be used to produce the beat frequency. The actuation of relay 13 opens an obvious circuit through the winding of the normally operated relay 14, which, in releasing, closes a circuit through the left-hand winding of relay 35, and left-hand normal contact of relay 27. Relay 35 operates and illuminates, through an obvious circuit, lamp 47 thereby signaling station B that station A is calling. Relay 35 in operating locks up through a circuit including grounded battery, its right-hand winding and left-hand contact and the right-hand normal contact of relay 27 to ground. The operator at station B, in response to the illumination of lamp 47 inserts 105 into a jack 28 the plug 34 of cord circuit C located at station B. This causes the operation of relay 27 through a circuit similar to that traced for the operation of relay 15. Relay 27 in operating opens at its right-hand normal contact, the locking circuit of relays 35 which releases and extinguishes lamp 16. Marginal relay 36 and 16 are not operated 110 at this time. A conversational path is now completed between stations A and B over the line L, and subscribers' lines associated with the respective stations may be connected by any of the well known methods used in connection with local switchboards.

If, during the conversation it is desired to 130

signal the operator at station A, relay 29 is operated by the actuation of the ringing key 2 in the same way that relay 3 is operated. Relay 29 in operating applies double frequency ringing current to the line L from the source 38. This current passes over the line through the normal contacts of relay 3 into the receiving circuit Y which is similar to the receiving circuit shown associated with station X. A normally operated relay similar to relay 14 is caused to release and places ground on conductor 31 which short-circuits the winding of relay 17 through the right-hand alternate contact of relay 15, which is in the operated condition by reason of the previous insertion of plug 34 into jack 1. This causes a reduction in the resistance of the circuit of marginal relay 16 which now operates and causes the illumination of the lamp 32 through an obvious circuit, notifying the operator at station A that station B desires to converse. The listening key 37 is then actuated, connecting an operator's telephone set, (not shown), to the conductors of the cord circuit, thereby establishing a conversational connection with the operator at station B. When relay 16 operates it locks up through a circuit including grounded battery, its winding and the left-hand contact, resistance 39 and the lower left-hand normal contact of key 37 to ground. This locking circuit is opened when key 37 is actuated. Relay 16 accordingly releases and extinguishes lamp 32.

Since the apparatus at either end of the line L is similar, a signal may be similarly transmitted from station B to station A to operate relay 30 and cause the lighting of lamp 33 in the same manner as relay 35 is operated and lamp 47 illuminated as previously described.

When the cord circuit plugs at each station are withdrawn from their respective jacks, it is evident that the circuit paths through the sleeve relays at each station are opened so that these relays then release and all apparatus is restored to normal.

The preceding description explains how a two frequency source of current may be applied to a long distance telephone transmission line. It is evident, however, to one skilled in the art, that a source of ringing current consisting of more than two frequency components might be used if desired with a slight modification of receiving circuit X. In that event, assuming for instance, instead of a two component source of current as shown at 18, a three component source is used. It would then be necessary to use a selective circuit composed of three resonant paths as shown in Fig. 2 instead of two, as shown in Figure 1. The output circuit of the tube 11 would then be tuned to some predetermined effect resulting

from the combination of the several frequencies. Where three frequencies are used, the receiving circuit, for instance, might be tuned to the sum of all three frequencies. The use of more than two frequencies gives a freedom from interference greater than that obtained from only two components. However, in practice, it has been found that the use of two components is, in general, satisfactory.

What is claimed is:

1. The method of operating a signal over a transmission line designed to efficiently transmit voice frequency currents which comprises simultaneously applying a plurality of audio-frequency currents to said line, separately receiving the different components of said simultaneously applied currents, combining the different components, integrating the beat frequency component of said combined audio-frequency currents, rectifying the beat frequency component, and translating the rectified current into a signal.

2. In a signaling system, a telephone line designed for the efficient transmission of speech frequency currents, means for transmitting a pair of fixed frequencies over said line simultaneously, means associated with said line for combining said frequencies to produce a difference frequency, said difference frequency being within the voice range, a signal, and means associated with said line responsive to the difference frequency for operating said signal.

3. A transmission line divided into an inner and two outer sections, devices for inductively uniting the three sections, means associated with the inner section for applying electrical current to said inner section for transmitting telegraph messages thereover, means associated with one of the outer sections of said line for applying at will a pair of audio-frequency currents to said line, means associated with the other outer section of said line for combining said frequencies to produce a beat frequency, and a signal controlled by said beat frequency.

4. In combination, a transmission line, means for transmitting telegraph messages thereover, means for applying simultaneously a pair of speech frequency currents at will to said line whose difference frequency is within the voice range, and a receiving circuit including a tuned circuit for each of said speech frequency currents, means for combining the pair of speech frequency currents to produce the difference frequency, a circuit resonant to the difference frequency, and a signal device actuated by the difference frequency.

5. In a signaling system, a transmission line composed for simultaneous telephony and telegraphy, means at one end of said line for transmitting audio-frequency cur-

rents and for transmitting a definite combination of audio-frequency currents over said line, means at the other end of said line responsive only to said definite combination 5 of audio-frequency currents to produce a unidirectional current, a signal and means to actuate said signal responsive to said unidirectional current.

6. In a signaling system, a transmission 10 line composed for simultaneous telephony and telegraphy, means at one end of said line for transmitting audio-frequency currents and for transmitting a definite combination of audio-frequency currents over 15 said line, a plurality of circuits at the other end of said line respectively resonant to the component frequencies of the definite combination of audio-frequency currents transmitted over said line, signal controlling 20 means responsive to a predetermined combination of the incoming audio-frequency currents, and a tuned circuit inductively coupled with said resonant circuits selectively sensitive to the predetermined combination 25 of incoming frequencies for effecting the operation of said signal producing means.

7. In a signaling system, a transmission line composed for simultaneous telephony and telegraphy, a link circuit for extending 30 said line, means associated with said link circuit for transmitting audio-frequency currents over said line, a plurality of current sources of different frequencies within the range of audibility, manual switching means 35 associated with said link circuit for applying said current sources to one end of said line simultaneously, receiving means at the other end of said line consisting of a plurality of circuits, each resonant to a different one of 40 said simultaneously applied audio-frequency currents, a plurality of thermionic tube circuits for integrating the difference frequency component of the simultaneously applied 45 audio-frequency currents and for rectifying it, and signaling means responsive to said rectified current.

8. In a signaling system, a transmission

line composed for simultaneous telephony and telegraphy, a link circuit for said line, means associated with said link circuit for transmitting audio-frequency currents over said line, a plurality of current sources of different frequencies within the range of audibility, manual switching means associated with said link circuit for applying said current sources to one end of said line simultaneously, receiving means at the other end of said line consisting of a plurality of circuits, each resonant to a different one of 50 said simultaneously applied audio-frequency currents, two thermionic tubes inductively coupled with said resonant circuits, the output circuit of one tube tuned to the difference frequency of the simultaneously applied 55 audio-frequency currents and the other of said tubes rectifying the difference frequency current, and signaling means responsive to the rectified current.

9. In a signaling system, a transmission line designed to efficiently transmit voice 60 frequency currents, a link circuit for said line, means associated with said link circuit for transmitting audio-frequency currents over said line, a plurality of current sources of different frequencies within the range of audibility, manual switching means associated with said link circuit for applying said current sources to one end of said line simultaneously, responsive means at the other end of said line consisting of a plurality of circuits, each resonant to a different one of said 65 simultaneously applied audio-frequency currents, two thermionic tubes inductively coupled with said resonant circuits, the output circuit of one tube being tuned to the difference frequency of the simultaneously applied 70 audio-frequency currents and the other of said tubes rectifying the difference current, and signal means responsive to the rectified current.

In witness whereof, I hereunto subscribe my name this 21 day of March, A. D. 1921.

ROBERT C. MATHEWS
